UNITED STATES PATENT OFFICE.

FRANK H. WHEELOCK, OF WASHINGTON, DISTRICT OF COLUMBIA,
ASSIGNOR, BY DIRECT AND MESNE ASSIGNMENTS, TO THE PATENT
FIN HOT WATER HEATING COMPANY, OF WASHINGTON, DISTRICT
OF COLUMBIA, A CORPORATION OF VIRGINIA.

A MEANS OR DEVICE FOR IMPROVING THE CIRCULATION AND AUGMENTING THE HEATING CAPACITY OF THE FLUID IN HEATING SYSTEMS.

No. 830,268.

Specification of Letters Patent.

Patented Sept. 4, 1906.

Application filed October 27, 1905. Serial No. 284,877.

To all whom it may concern:

Be it known that I, FRANK H. WHEELOCK, a citizen of the United States, residing at Washington, District of Columbia, have invented new and useful Improvements in Means or Devices for Improving the Circulation and Augmenting the Heating Capacity of the Fluid in Heating Systems, of which the following is a specification.

10 My invention relates to a device or means for improving the circulation and augmenting the heating capacity of the fluid in heating systems and the like, more particularly, though not exclusively, intended for use in 15 hot-water heating systems for buildings.

The invention resides in the device and in the combination thereof in a fluid-conduit, as hereinafter set forth and illustrated.

That which is regarded as new is set forth 20 in the clauses of claim appended to the description.

In the accompanying drawings, illustrating what I regard as the best-known embodiment of my invention, Figure 1 is a perspective view of the device; Fig. 2, an edge view; Fig. 3, a top plan; Fig. 4, a side view. Fig. 5 is a view of a heat-generator, one of the devices arranged in a fluid-pipe in the fire-box thereof, a radiator included in the pipe system, and another of the devices incorporated 25 in the circulation-pipe adjacent the latter; Fig. 6, a plan of a suitable blank from which to construct the device.

In the drawings the reference-numeral 1 designates the body of the device, which has 30 parallel side edges 2 to fit against the inner wall of the pipe or tube in which the article is arranged for use and which serve as one convenient means by which it is connected 35 and held in stationary position for use therein. I have found a body of the character referred suitable in use, but do not wish to restrict my invention to the form or shape thereof.

40 The body 1 is provided at opposite sides of the longitudinal median line thereof with laterally-projecting concavo-convex end wings 3, which I term "deflectors," one of 45 which projects from one face of said body and the other from the opposite face thereof 50 and the outer edges of which conform to and

substantially fit the wall of the pipe in which it is arranged. The wings taper from their bases to the tips, presenting substantially V-shaped concavo-convex faces, and are disposed obliquely or slantingly with respect to the parallel edges 2, inclining inwardly and upwardly to provide centripetal deflecting-surfaces 4, that will deflect those portions of fluid upon which they act and conduct the 60 same to and discharge it at the center of the fluid column. It will be observed that the deflecting-wings are at the end of the body portion, so that the fluid deflected thereby immediately constitutes a part of the undivided fluid column, and, furthermore, that the deflecting-surfaces of the wings run in the same direction, one being operatively in advance of the other, so that one does not oppose the action of the other, with the result 70 that a whirling motion is imparted to the fluid as it leaves the device. The device may be conveniently constructed of a blank such as shown in Fig. 6, having a triangular section removed from one end thereof to provide 75 portions *a*, that may be readily fashioned into the centripetal deflector-wings above described.

In Fig. 5 the utilization of the device arranged in a water-tube in the fire-box of a 80 furnace F is illustrated, and in this figure it is also shown incorporated in a circulating-pipe of a heating system outside of the furnace or other heat-generator, the system including a radiator R. It may be disposed in 85 the system at any point found desirable. It makes possible the installation of an effective hot-water heating system in connection with a small stove as the generator, and it may be readily introduced into the circulation-pipes 90 of existing systems and secures marked improvement in the circulation and heating capacity thereof, with a very material reduction in the consumption of fuel.

Without desiring to restrict my invention 95 to any theory or law governing the operation thereof I attribute the beneficial results of its use to the fact that those portions of the fluid column which flow in contact or close to the wall of the conduit, pipe, or tube, and 100 therefore become first heated and are always of higher temperature than that which flows

- centrally in the conduit, is deflected and conducted to the center, equalizing the temperature of the entire column, and this effect is facilitated by the fact that the fluid-passage is slightly constricted, whereby the pressure and the velocity of flow are increased, causing an agitation of the fluid column and imparting an impetus to the circulation.
10. Whatever be the reason therefor, the device produces a decided improvement in circulation and an increase in work, which is evidenced by a markedly greater heat-giving capacity.
15. In actual practice the utility of the appliance has been demonstrated. In one installation a single three-quarter-inch pipe (one-fourth the interior area usually employed in the circulation-pipes of hot-water heating systems) disposed in an ordinary hot-air furnace and having one of these devices incorporated therein and including in the circuit two radiators of usual make has served to effectually and equally heat radiators of more than seventy square feet of radiator-surface with a greatly-reduced expenditure of fuel.
20. The device has been employed in a pipe disposed in the fire-pot of an ordinary small heating-stove and connected up with radiators and excellent results secured.
25. While I have described my invention more particularly in its use in connection with hot-water heating systems, I do not restrict the same thereto, but claim the device or appliance in respect of all the uses of which it is capable.
30. Having described my invention, I claim—
1. A means for improving the circulation of a circulating-fluid system consisting of a body provided with oppositely-projecting centripetal deflecting end wings.

2. The combination with a fluid-circulating system, of a device incorporated therewith within the piping thereof and provided with a centripetal deflector end wing. 45
3. The combination with a fluid-circulating system, of a device incorporated therewith within the piping thereof and provided with centripetal deflecting end wings.
4. The combination with a heat-generator and a fluid-circulating system part of which is arranged in the fire-box thereof, of a device incorporated into the piping of said system within said fire-box and provided with centripetal deflecting end wings. 50
5. A means for improving the circulation of a circulating-fluid system, consisting of a body provided with oppositely-projecting centripetal deflecting wings.
6. The combination with a fluid-circulating system, of a device incorporated therewith within the piping thereof and provided with centripetal deflecting-wings. 60
7. The combination with a heat-generator and a fluid-circulating system part of which is arranged in the fire-box thereof, of a device incorporated in the piping of said system within said fire-box, and provided with centripetal deflecting-wings. 65
8. A means for improving the circulation in a circulating-fluid heating system, consisting of a device located in a fluid-conduit of the system having means for imparting a centripetal whirling motion to the fluid column. 70

In testimony whereof I have hereunto set my hand in presence of two subscribing witnesses.

FRANK H. WHEELOCK.
